UNITED STATES PATENT OFFICE.

EDWARD E. KILBOURN, OF NEW BRUNSWICK, NEW JERSEY.

CIRCULAR-KNITTING MACHINE.

SPECIFICATION forming part of Letters Patent No. 408,110, dated July 30, 1889.

Original application filed June 14, 1887, Serial No. 241,243. Divided and this application filed May 9, 1889. Serial No. 310,077.
(No model.)

To all whom it may concern:

Be it known that I, EDWARD E. KILBOURN, a citizen of the United States, residing at New Brunswick, in the county of Middlesex and 5 State of New Jersey, have invented certain new and useful Improvements in Circular-Knitting Machines; and I do hereby declare the following to be a full, clear, and exact description of the invention, such as will enable others skilled in the art to which it appertains to make and use the same.

This invention has reference to cylinder knitting-machines in which a circular series of needles is employed for circular work and 15 also for reciprocating work.

The said invention is illustrated in the accompanying drawings, and is fully described in the following specification and claims, the present case being a division of application, 20 Serial No. 241,243, filed by me June 14, 1887.

The object of this invention is to facilitate the work of attending to this class of machines by providing means for holding down the work during the operation of narrowing, 25 and when it is desired to cast off the work, as in the case of a finished article.

It has also for its object to provide means for automatically throwing more or less of the needles out of and into operation, in combination with a reciprocating thread-guide, 30 for the purpose of narrowing and widening the work.

In the accompanying drawings, Figure 1 represents a front view of a circular-knitting machine embodying my invention. Fig. 2 represents a view of the rear of the same. Fig. 3 is a transverse section of said machine through the axis of the needle-cylinder, some parts being represented in elevation. Fig. 4 is a longitudinal section of a portion of the machine to the left of the axis of the knitting-cylinder. Fig. 5 represents the corresponding longitudinal section of the other portion of the machine to the right of said axis. Fig. 45 5^a is a view of the needles employed in the machine. Fig. 5^b is a partial plan view, on a reduced scale, showing a part of the operating mechanism. Fig. 6 is a section of a part of the nosing, showing the hook-partitions. Fig. 50 7 is a central vertical section of the cam-cylinders. Fig. 8 represents a view of the in-

side of one of the carriers for the pickers. Fig. 9 is a view of the outside of the same. Fig. 10 is a top view of the same. Fig. 11 is a vertical transverse section of one of said carriers, and Fig. 12 represents a similar partial section showing another form of guiding-groove. Fig. 13 is a view of parts of the mechanism detached.

The machine herein shown is generally used for knitting seamless stockings by first 60 knitting the leg by a continuous circular movement operating all of the needles of the knitting-cylinder. The heel is then formed by a gang of needles used for reciprocating work, which are operated by the reciprocation of the proper operating mechanism, during reciprocating work a certain portion of the needles at each side of the gang being successively thrown out of operation to effect the 65 narrowing of the web, which is then widened by throwing the said needles successively into operation in a reverse order. The foot of the stocking is then formed by a continuous circular movement of the operating devices by 70 operating all of the needles, and the stocking is finished by forming the toe in the same manner as the heel. While this is the most general mode of proceeding in using the machine, it may also be used by commencing the 75 stocking at the toe and reversing the order of operation here described. The needles of the reciprocating gang I term the "fashioning-needles," and shall so refer to them in the following description.

The needles preferably used in the machine are latch-needles having pivoted latches of the usual construction, and the shank of each is secured to or made in one piece with a projection or nib, upon which the cams act for 80 the purpose of moving the needles. The needles are arranged in a circular series and are fitted to slide up and down in the groove of the knitting-cylinder A and its nosing A'. The needles are operated by means of two 85 cams, which, as shown in section at B B', Fig. 3, and in detail Fig. 7, are arranged one above the other and secured to cam-cylinders B² B³, which are concentric with the circular series of needles and are fitted to turn around the 90 knitting-cylinder A. The lower cam-cylinder is supported by a ring or support b, (see Figs. 100

3, 4, and 6,) and the upper cam-cylinder E² is supported upon the lower. The lower cam-cylinder B³ is held in place by means of studs b⁴, secured to the ring-bearing b, which studs 5 fit in a dovetailed groove b' of the cam-cylinder. The upper cam-cylinder is held in place by means of screws b⁵, whose heads are received in a groove b² of the upper cam-cylinder. The upper cam-cylinder B² is employed, 10 preferably, to operate the gang of needles, which are put bodily out of operation when the heel and toe of a stocking are knit, the lower cam-cylinder B³ being employed, preferably, in operating the gang of needles which 15 are employed, in combination with a reciprocating thread-guide, to knit the heel and toe of the stocking. In order to adapt the needles to the positions of these cams, those needles which are to be operated by the upper 20 cam B have their nibs arranged at the required distance from their heads to be operated by that cam for circular work, and those needles which are to be operated by the cam B' during widening and narrowing—namely, the 25 fashioning-needles—have their nibs arranged at the required distance from their heads to be operated by that cam for both circular work and reciprocating work.

All the needles are guided when moving 30 lengthwise of their shanks by being fitted to slide in grooves of the knitting-cylinder A and its nosing A'. The nosing A' is not secured rigidly to the knitting-cylinder A, but is made adjustable by being fitted to slide up 35 and down within it without being turned. This is accomplished by supporting said nosing upon a screw-threaded ring A³, whose screw-threads engage with an internal screw of the knitting-cylinder, so that the said ring 40 holds the nosing in position to which it may be adjusted. By turning this screwed ring the nosing may be adjusted higher or lower to correspond with the lengths of the loops that are being drawn down by the needles. 45 The nosing A' is prevented from turning, preferably by means of a pin and an upright groove, the pin being secured to the nosing and the upright groove being formed in the inner face of the knitting-cylinder A.

50 When the entire series of needles is operated for knitting straight circular work—such as the leg of a stocking—both cam-cylinders B² B³ are caused to revolve continuously and simultaneously, so that each needle of the entire circular series is caused in succession to move lengthwise to and fro as required, to take the yarn for the loop formed by it and to cast off the preceding loop or stitch. For this purpose the two cam-cylinders are connected by gearing with and given a continuous rotary motion by the main driving-shaft D. The connection between the lower cam-cylinder B³ and the main driving-shaft D is by means of a main wheel e, secured to the 55 lower cam-cylinder B³, the intermediate wheel e', fitted to turn on a stud e², the pinion e³, secured to the upper end of the upright shaft

e⁴, the beveled pinion e⁵, secured to the lower end of the shaft e⁴, the beveled wheel e⁶, gearing into the beveled pinion e⁵, the beveled pinion e⁷, connected with the beveled wheel e⁸ and fitted to turn upon a shaft e⁸, and a beveled wheel e⁹, which is secured to the main driving-shaft B and revolves with it. When, therefore, the driving-shaft is caused to revolve in the direction indicated by the arrow in Fig. 1, the lower cam-cylinder is caused to revolve continuously in the direction indicated by the arrow in said Fig. 1. 70

The upper cam-cylinder B² is preferably 80 caused to revolve by being connected with the lower cam-cylinder B³, and the most convenient method of connecting the two cam-cylinders is by means of a lug c', secured to the cam-cylinder B³, which receives its revolving 85 movement directly from the driving-shaft B, and a pivoted latch or lug c², secured to the other cam-cylinder B² and adapted to be engaged by the lug c'. When the cylinder B³ is revolved in the direction indicated by 90 the arrow, Fig. 1, the lug c' will engage the latch c² and the two cam-cylinders will revolve together. The cam-cylinders can be turned by hand independently of each other, and if the cam-cylinder B³ be rotated backward 95 the lug c' will pass under and lift the latch c², allowing the cam-cylinder B² to remain stationary.

I provide a thread-guide E to feed the thread to the entire series of needles when 100 knitting circular work. This thread-guide is mounted upon and carried by the cylinder B², and delivers the yarn to the needles in succession before the cam-cylinders operate upon their nibs. In order that this circular thread-guide may be readily moved out of its operative position when the heel and toe of the stocking are to be knit, it is pivotally secured 105 upon the cam-cylinder B², and a suitable locking device is provided to lock the said thread-guide and hold it both when in and out of operative position, as more particularly described and shown in my application Serial No. 310,078.

In order that the latches of the needles may 115 be kept from accidentally flying up when knitting circular work and that they may be positively thrown down, I provide the latch-guard or follower f⁴, which is connected with the stock of the thread-guide, and is adapted 120 to be thrown into and out of operative position with said thread-guide.

The heads of the needles work in combination with the nosing A', and the tightness of the loops drawn by the needles is determined 125 by the position of the upper edge of said nosing. The partitions of this nosing between the needles consist of hooks a, with which the loops engage, so that when the needle-heads are raised the loops of the work are held by 130 the hooks and do not rise with the needle. The hook-partitions, as shown in Fig 6, have each two inclines a' and a²—one above and one below the projection constituting the

hook. The hook is located slightly above the casting-off point of the needles, so that as a needle descends, carrying the thread supplied by the thread-guide, the thread is engaged by 5 the inclines a' and a proper amount drawn off to form a loop. The further descent of the needle brings the thread on each side of the previously-formed loop against the inclines a^2 , drawing the loop tightly against the needle. 10 This incline a^2 extends inward a sufficient distance to limit the downward movement of such former loop and the web, which forces the needle to cast off. As it does so, the elasticity of the thread brings the loop cast off inward, and, as the part of each partition just beneath the hook extends inward as far or slightly farther than the outer face of the body of the needle, all portions of the knitted material after they have once left the needle 15 are kept out of the path of the needle, whereby the latter is prevented from rising or passing through a loop a second time. This part of the hook-partition, also, in the operation of starting a web or article, serves to hold the 20 thread first taken down by the needle inward and against the outer face of the needles in such a position that on a second depression of the needle perfect loops are formed and the web or article begun without any other 25 operation of setting up the same. 30

In order to hold the upper cam-cylinder out of operation when reciprocating work is being done, I provide a locking device for such cylinder, which consists, preferably, of a 35 notched latch F , which engages a lug a' on the cam-cylinder B^3 . This locking-latch may be thrown into and out of operation by any preferred means. In my application Serial No. 241,243 I have shown and particularly de- 40 scribed one form of mechanism for effecting this result.

During the reciprocating work I prefer to cause the cam-cylinder B^3 to move to and fro by a portion of the same gearing which is 45 used for operating it during circular work and to employ supplementary gearing to complete the movement. I prefer in this connection to use a supplementary driving-shaft D' for reciprocating work, and to connect so much 50 of the gearing as is then used with that supplementary driving-shaft. The portion of the main gearing previously described, which is used in the said machine for reciprocating work, consists of the main wheel e , the inter- 55 mediate wheel e' , the pinion e^3 , the upright shaft e^4 , the beveled pinion e^5 , and the beveled wheel e^6 . The other portion of the main gearing, which remains connected with the main driving-shaft, consists of the two wheels e^7 60 and e^8 . In order that the former portion of the gearing may be reciprocated for reciprocating work, the beveled wheel e^6 is not made fast to the beveled wheel e^7 , and the connection of the said beveled wheel e^6 with the bevel- 65 ed wheel e^7 for circular work consists of dis- connectible drivers, comprising, preferably, two lugs h h' , one of which is secured to the

back of the beveled wheel e^6 , while the other lug is connected with the beveled wheel e^7 , which is driven by the driving-shaft B . This 70 mode of connection permits the wheel e^6 to be rotated to and fro without affecting the driving-shaft D .

The supplementary driving-shaft is connected with the beveled wheel e^6 through the 75 intervention of a reciprocating rack H and a pinion e^{10} , which is driven by said rack, and is connected with the beveled wheel e^6 . The stock of the reciprocating rack H is fitted to slide in bearings connected with the main 80 frame, and it is connected by a connecting-rod H' with a crank H^2 , which is secured to the shaft H^3 , and this crank-shaft is connected with the supplementary driving-shaft by means of beveled wheels e^{11} and e^{12} . In order 85 that the said reciprocating mechanism may be connected with and disconnected from the cam-cylinder B^3 , the connection is made through the intervention of a clutch member I, Fig. 13, whose hub is fitted to slide upon 90 pinion-shaft e^8 , and is connected with it by a spline or feather of the usual construction. The clutch member I has a tooth i , which is adapted to engage a notch formed in the hub i' of the wheel e^6 , and the portion of the main 95 gearing connecting it with the cam-cylinder B^3 and the said cam-cylinder is caused to reciprocate by the continuous revolution of the driving-shaft D' . This clutch member I may be moved by means of a shipper, one arm of 100 which J is forked and engages a groove of the clutch-member, and the other J' has the form of a handle, the two parts being connected by a vertical shaft suitably mounted on the main frame. 105

The yarn is fed to the fashioning-needles during reciprocating work by means of a supplementary thread-guide E' , which has an arm E^2 extending into the path of a projection or projections on the cam-cylinder B^3 , by 110 means of which said thread-guide is reciprocated with said cylinder in advance of the cam B' . This reciprocating thread-guide is pivotally mounted in the end of an arm E^4 , which is in turn supported by a standard E^3 , 115 and means are provided for locking the said thread-guide when in its operative position, and also when it is swung out of engagement with the knitting-cylinder, as more particularly described in my application Serial No. 120 310,078.

The fashioning-needles are raised and lowered out of and into operative position during narrowing and widening by means of pickers K , Figs. 8, 9, 10, 11, and 12, one for each side 125 of the gang of fashioning-needles. Each of these pickers is fitted to slide up and down in a carrier L , which is moved to place the picker in position to operate upon the required needle. Each carrier is fitted in grooves kk' 130 in the frame-work of the machine, said grooves being concentric with the series of needles, so that the pickers may operate successively upon the needles in exactly the same manner.

These grooves being concentric with the knitting-cylinder, and the carriers being segmental in form, the said carriers will work in the same grooves on opposite sides of the 5 knitting-cylinder. This construction enables me to employ short pickers and construct them of the same size for both sides of the machine. If preferred, the ends of the carriers may be grooved, and the grooves k k' may be 10 replaced by circular ribs, as shown at k^* , Fig. 12.

In order that the same picker may be used 15 to move the needle for narrowing out of its working position, and to move it for widening into its working position, each picker is provided with two lugs k^2 k^3 , Figs. 8 and 11, one of which k^2 acts beneath the supplementary nib of the needle-shank and pushes the needle 20 out of its working position for narrowing, while the other k^3 acts upon the upper side of 25 said nib and pulls it back into its working position for widening. In order to effect this, these two lugs are placed in different vertical and horizontal planes. (See Fig. 11.) The 30 pickers are caused to rise and fall by means of a reciprocating cam K' , which is preferably fitted to turn upon the stock of the knitting-cylinder below the knitting-cams, and each picker K is provided with a pin k^4 , which 35 engages the groove of the said cam K' for operating the said picker. The picker-cam is provided on its periphery with gear-teeth k^5 , which engage with the teeth of a gear-segment k^6 , which is fitted to vibrate upon a stud 40 k^7 , secured to the frame of the machine. To this segment is secured a second segment n , whose teeth are engaged by those of a rack N , which is supported in guides and has its shank connected by a pin with an upright 45 lever N' , whose lower end is pivoted to the frame of the machine. The lever N' is formed in the shape of a yoke, and has two projections n^2 n^3 within the range of the two members n^4 n^5 of a cam N^2 , which is secured to the 50 crank-shaft H^3 of the machine, which is driven by the supplementary driving-shaft D' . It will be seen that a revolution of the shaft H^3 will cause a reciprocation of the rack M , segments n and k^6 thereby actuating the cam K' and the pickers K .

The best time at which a needle can be moved out of operation for narrowing the work is in the interval of the knitting movement of the needle, which occurs after the 55 cam B' of the cam-cylinder B^3 , while being moved in a direction toward the side of the fashioning-needles at which the needle is to be raised, has passed by the nib of that needle and before the cam is returned to the position of the nib of that needle. On the other hand, the needle which is to be moved into 60 its operative position for widening the work must be moved by the picker before the leading end point of the cam B' of the cam-cylinder B^3 reaches that needle. The members of the cam N^2 which operate the picker-cam K and the picker-cam groove should therefore be

so shaped and the movement of the said parts be so timed as to move the pickers K at the said time, as above set forth.

When a needle is moved out of its operative position, it should be held positively from returning until it is again wanted for widening the work. This is effected by means of the needle-holder m , Figs. 8, 9, 10, and 11, one 75 of which is used with each picker and is connected with the respective carrier L thereof. This needle-holder m consists, preferably, of a ring-segment, which is supported and fitted to move in a groove located in the inner face 80 of the carrier L , and is supported at its inner edge in a groove formed by two collars m' of the knitting-cylinder. The needle-holder is movable in the carrier and the spring m^3 is applied to move it independently of the carrier. When the carrier is moved in the direction of the arrow m^4 , Figs. 8 and 9, to place 85 the picker in position to move a needle out of the working position, the end of the holder m is pressed laterally against the shank of that needle, the spring m^3 yielding to permit the carrier to move without carrying the holder with it. When the needle is raised by the picker, the spring m^3 forces the needle-holder beneath the raised needle and holds 95 it positively in its raised position. The circular extent of the needle-holder is sufficient to hold all the needles which are successively raised for narrowing the work. When the carrier is moved outward—that is, in the direction indicated by the arrow m^2 in Fig. 9—to place the picker in position for drawing a 100 needle into the working position for widening, the needle-holder is moved with the carrier by reason of the pin m^6 of the needle-holder, which engages a slot m^5 in the carrier 105 and will be engaged by the end of said slot. The holder is therefore moved from beneath the needle upon which the picker is to operate, thus releasing it.

In order that narrowing or widening may be effected, the carrier must be moved to an extent equal to the distance between the centers of the needles, so as to remove the picker from the needle upon which it has already 115 operated to the next needle in the gang. In the machine represented in the drawings both of the carriers L are moved equally, but in alternate succession, so that the needles at the opposite side of the gang of fashioning-needles 120 may be raised or lowered alternately and successively.

The alternating movement of the pickers K with an interval of rest after each carrying or shifting movement of the picker is effected by means of the driving-shaft which 125 operates the cam-cylinder B^3 . Each carrier L is fitted with a worm-segment l , which is engaged by a screw l' , secured to the shaft l^2 , which is fitted both to turn and to move 130 endwise in its bearings. Each screw-shaft is fitted with a pinion l^3 , the teeth of which engage with those of a wheel l^4 , which is a driving-wheel common to both pinions l^3 l^4 , as

shown in Fig. 1. This wheel l^4 is caused to turn continuously during reciprocating knitting. The gearing between the screws $l' l'$ and the supplementary driving-shaft is so proportioned that each screw is caused to revolve one-half of a revolution for each revolution of the crank-shaft H^3 , which imparts a reciprocating movement to the thread-guide E' , as before described, and the pitch of the screws $l' l'$ is double the pitch or gage of the needles in the series, so that a half-turn of the screw is sufficient to move the carrier which it controls and the lifter of the carrier from one needle to the next in the series. The screws are given an endwise movement for the purpose of giving the carrier a period of rest before each advance by a cam, and I prefer to use two cams for each screw and to arrange these in the form of cam-collars l^6 , Fig. 3. These cam-collars, one of which is shown in Fig. 3, are located at the opposite sides of the bearings l^6 , in which the screw-shaft revolves, and the screw-shaft is fitted with pins l^7 , one of which is shown in Fig. 3, which bear against the collars, so that as these pins move during the turning of the screw along the inclined faces of the cam-collars the screw-shaft l^8 and screw l' are caused to move endwise, as clearly shown and described in my application Serial No. 310,079.

During the narrowing of the work the carrier is caused to move endwise—that is, to approach the middle of the gang of fashioning-needles then at work with the reciprocating thread-guide—and during the widening of the work the carrier is caused to move outward. In order that these movements in reverse direction may be obtained from the driving-shaft while always revolving in the same direction, the screw-driving wheel l^4 is connected with the supplementary driving-shaft D' of the machine through the intervention of gearing, comprising two racks, or gear-wheels acting as racks, which are moved alternately in opposite directions. The screw-driving wheel l^4 , which is fitted to revolve upon a stud secured to the frame of the machine, has secured to its hub a beveled pinion l^8 , Fig. 3, which engages with a beveled wheel l^9 , whose hub l^{11} is fitted to turn upon the stock of the knitting-cylinder A . A corresponding beveled wheel l^{10} having its teeth opposed to the teeth of wheel l^9 , is also secured to the same hub l^{11} , so that the two wheels revolve together. These wheels I prefer to denominate "change-wheels." At the side of the hub of these beveled wheels which is opposite to the beveled pinion l^8 a second beveled pinion l^{12} is arranged, and this beveled pinion is connected to the supplementary driving-shaft D' through the intervention of the wheel l^{13} , secured to the hub of the beveled pinion l^{12} , the intermediate wheel l^{14} , secured to an intermediate pinion l^{15} , (shown in dotted lines in Fig. 2,) the pinion l^{16} , (also shown in dotted lines, Fig. 2,) secured to the crank-shaft H^3 , and the beveled wheels $e^{11} e^{12}$, which

impart motion from the supplementary driving-shaft D' to the crank-shaft H^3 . The diameter of the pinion l^{12} is smaller than the space between the faces of the reversely-beveled wheels l^9 and l^{10} , so that it can operate in connection with one of said beveled wheels without touching the teeth of the other, and the shifting of the driving-pinion from one of said wheels to the other changes the direction of rotation of said wheels, thereby reversing the direction of rotation of the screws $l' l'$ and the carriers L .

In order that the driving-pinion may be shifted automatically from one wheel to the other, the hub of said driving-pinion l^{12} and of the wheel l^{13} , secured to said pinion, is fitted to turn upon a stud l^{17} , which is movable, it being held by an arm l^{18} , which is fitted to swing upon the axis of the intermediate wheel l^{14} , so that the driving-pinion may be shifted from one of the change-wheels $l^9 l^{10}$ to the other without affecting the engagement of the wheels l^{13} and l^{15} . The driving-pinion is also provided with a stud or roller l^{19} , Fig. 3, and the hub l^{11} of the change-wheels is provided with a rail l^{20} , secured thereto between said change-wheels. Two segments l^{21} are preferably secured, by means of screws, between the change-wheels, the teeth of the segment corresponding with those of the change-wheels. When the driving-pinion impelling either of the change-wheels causes the appropriate segment to come into gear with the pinion-teeth, said pinion engages said segment and is shifted from one of said change-wheels to the other and the end of the rail l^{20} is in the proper position to permit the stud or roller l^{19} of the driving-pinion to pass around it during this shifting operation and the said rail serves to hold said driving-pinion in engagement with one or the other of said change-wheels by means of the stud l^{19} . The extents of the portions of the change-wheels which are between the segments and which are operated by the driving-pinion before shifting determine the number of turns imparted to the carrier-screw, the number of times the carriers are moved, and the number of needles that are moved into and out of operation in widening and narrowing the work. As the wheels l^9 and l^{10} are moved alternately in opposite direction, they operate to change the direction in which the carriers are moved and are therefore denominated "change-wheels." It will be noticed that the segments l^{21} , which connect the change-wheels, are set behind or within the line of the teeth of said wheels. This is convenient because it permits the two beveled wheels, with their hub, to be readily cast in one piece. It also permits machines of the same pattern to be readily adapted to the widening and narrowing of work to a greater or less extent by setting the segments farther apart or nearer together, thereby increasing or diminishing the number of teeth on the change-wheels between the two segments. It is also advan-

tageous because it permits one of the said change-wheels to operate the driven pinion β , as the segments are within the line of the teeth of the change-wheels and the said segments do not interfere with said pinion. When a change is made in the positions of the segments, the length of the rail β^0 must be correspondingly lengthened or shortened as the segments are set farther apart or nearer together.

By employing the mechanism above described the picker-carriers are given positive movements of exactly the required extent to shift the picker from one needle to the next at each side of the series, and there is no possibility of the carrier being shifted by accident or missing a movement or of being moved to a greater extent than is required. I also provide the machine with automatic means for shifting the belt from fast to loose pulleys on each of the driving-shafts B B' of the machine on the completion of certain predetermined movements, as shown, and particularly described in my application Serial No. 241,243; but these form no part of the invention herein claimed and a detailed description of them is not given.

The operation of the hook-partitions of the nosing of the knitting-cylinder is important in connection with the devices for narrowing and widening herein shown and described. As soon as a needle has been thrown up out of operative position at each side of the gang of fashioning-needles, such needles sustain all the weight or tension upon the web at that side of the machine, so that the web between such needles is not subjected to strain or tension during the remainder of the operation of narrowing and widening until those needles are returned to their operative positions. In order, therefore, to secure the proper casting off of the loops in the progress of the work during this period, it is customary for the operator to put a tension or strain upon that portion of the web by pressing it down and away from the needles with the finger or some instrument conveniently at hand. When a needle at the side of the fashioning-gang has been raised, the thread extends from the outer or farther side of this needle outward, and on the return of the thread-guide it is carried to the next needle. It is almost an impossibility to apply any tension sufficient to prevent the raising of the work at such points. The hook-partition of the nosing, therefore, not only supplies the place of a special tension on the web, but it acts to retain the loops on the needle or needles next adjacent to the last needle raised out of operation, which cannot be accomplished by any tension device.

In knitting during the process of narrowing, in consequence of withdrawal of all tension on the web or knitted material on needles next adjacent to the last needles thrown out of operation, there is a difficulty in securing the proper casting off of the loops from such

needles, and the hook-partitions perform an important service in respect to this part of the operation and effect this casting off with certainty in such a manner as to secure the best results.

The needle-operating cams, general actuating mechanism, and stop devices are made the subject of my application Serial No. 241,243, filed June 14, 1887; the thread-supplying devices the subject of my application Serial No. 310,078, filed May 9, 1889, and the narrowing and widening mechanism the subject of my application Serial No. 310,079, filed May 9, 1889, and are not claimed herein.

What I claim, and desire to secure by Letters Patent, is—

1. The combination, substantially as before set forth, of the knitting-cylinder, the cam which operates the gang of fashioning-needles for both circular work and reciprocating work, the cam which operates the other gang of needles for circular work, the gang of fashioning-needles having their nibs arranged to be operated by the said first cam, the other gang of needles having their nibs arranged to be operated only by the said second cam, and the hook-partitions of the nosing by which the work is prevented from rising.

2. The combination, substantially as before set forth, of the needle-cylinder, the cam-cylinder for operating the needles for reciprocating work, the needles, the picker, the carrier, and the hook-partitions of the needle-cylinder, which not only hold down the work during narrowing, but which press the stitches forward out of the way of the needles.

3. The combination, as before set forth, of a needle-cylinder, and cams for both circular and reciprocating work, with a gang of needles all of which are operated for circular work, but a portion of which are thrown out of operation for narrowing during reciprocating work, but which retain their stitches while out of operation, the said needle-cylinder being provided with stationary hook-partitions, which not only hold down the work during narrowing, but press the stitches forward out of the way of the needles.

4. The combination, with a needle-cylinder, of needles a part of which are thrown out of operation for narrowing during reciprocating work, but which retain their stitches while out of operation, and cams for operating the needles for circular and reciprocating work, the said needle-cylinder being provided with stationary hook-partitions between its needle-grooves, said partitions having inclines below the hooks to assist in casting off the stitches, and a part above said inclines and below the hooks for holding the stitches inward out of the way of the needles, substantially as described.

5. The combination, substantially as before set forth, of a needle-cylinder provided at the top with stationary hook-partitions between the needle-grooves, each of said hook-partitions having an outwardly-inclined point at

its upper end, the extreme point extending outside of the needles and having all parts of its inner edge below the hook extending as far as or farther inwardly than the outer face of the body of the needle, a series of needles, including narrowing-needles, needle-operating devices, and devices for narrowing and widening.

6. The combination, substantially as before set forth, of two cam-cylinders, one of which only operates during circular work, the gang of fashioning-needles for both circular and reciprocating work having nibs arranged to be

operated by the reciprocating cam for reciprocating work, the other gang of needles having nibs arranged to be operated by the first-named cam for circular work, and the hook-partitions, whereby the work is prevented from rising.

In testimony whereof I affix my signature in presence of two witnesses.

EDWARD E. KILBOURN.
